UNITED STATES PATENT OFFICE

161,439

HALTER OR SIMILAR ARTICLE

Jack Glick, Forest Hills, N. Y.

Application December 27, 1949, Serial No. 6,844

Term of patent 3½ years

(CL. D20—4)

To all whom it may concern:

Be it known that I, Jack Glick, a citizen of the United States, residing at Forest Hills, in the county of Queens and State of New York, have invented a new, original, and ornamental Design for a Halter or Similar Article, of which the following is a specification, reference being had to the accompanying drawing, forming a part thereof.

Fig. 1 is a front perspective view of a halter or similar article, showing my new design.

Fig. 2 is a similar view thereof as it appears in detached position.

The back of the halter is similar in appearance to the inside of the back as shown in Fig. 1.

I claim:

The ornamental design for a halter or similar article, substantially as shown and described.

JACK GLICK.
